ICE TRAY

John H. Roethel, Detroit, Mich., assignor to
Roethel Engineering Corporation, Detroit,
Mich., a corporation of Michigan

Application October 19, 1948, Serial No. 55,419

7 Claims. (Cl. 62—108.5)

1

This invention relates to liquid freezing receptacles and particularly, although not exclusively, to ice trays of the kind having a plurality of independent or individual molds or receptacles useful in refrigerators for quick freezing purposes.

An object of the invention is to provide an ice tray or other liquid freezing device having a frame structure for supporting a plurality of individual freezing receptacles and improved means for locating and positioning the receptacles with respect to the supporting frame structure.

Another object of the invention is to provide an icetray frame for receiving individual freezing receptacles and formed in improved manner from a single metal sheet or blank.

A further object of the invention is to provide an ice tray frame adapted to be produced at relatively low cost by press operations from a single metal blank and having improved means for positioning individual freezing receptacles therein and restraining them against displacement.

Still another object of the invention is to provide an ice tray embodying a tray frame and individual freezing receptacles, the bottom of the frame being ribbed to form spaces for the reception of receptacles and to assist in restraining displacement thereof within the tray frame.

Another object of the invention is to provide a tray frame for receiving individual freezing receptacles which will furnish increased contact area for the receptacles thereby accelerating the freezing of the liquid contents thereof, and which also may be manufactured in improved manner so as to have the requisite strength and rigidity to resist bending and twisting strains and thereby prolonging the useful life of the tray.

Other objects of this invention will appear in the following description and appended claims, reference being had to the accompanying drawings forming a part of this specification wherein like reference characters designate corresponding parts in the several views.

Fig. 1 is a perspective view of a tray frame carrying a number of individual liquid freezing receptacles or molds constructed in accordance with one embodiment of the present invention.

Fig. 2 is a section taken substantially through lines 2—2 of Fig. 1 looking in the direction of the arrows.

Fig. 3 is an enlarged section taken substantially through lines 3—3 of Fig. 1 looking in the direction of the arrows.

Fig. 4 is a perspective view of a tray frame constructed in accordance with another embodiment of the present invention.

Fig. 5 is a fragmentary perspective view of the tray frame shown in Fig. 4 with a plurality of receptacles supported therein.

Fig. 6 is a perspective view of one of the receptacles shown in Fig. 5.

2

Fig. 7 is a fragmentary sectional view taken substantially through lines 7—7 of Fig. 5 looking in the direction of the arrows.

Fig. 8 is a view generally similar to Fig. 5 illustrating the receptacles positioned within the tray frame in a different manner.

This application is a continuation in part of my forfeited application Serial No. 624,392, filed October 25, 1945.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the embodiment of the invention illustrated in Figs. 1 to 3 inclusive the tray frame 9 for receiving the individual freezing receptacles is formed from a single sheet or blank of material, such as sheet aluminum or steel. The sheet is stamped or drawn by means of suitable dies in a press to provide a generally rectangular tray frame comprising two parallel longitudinal side walls 10 and transverse rear and front end walls 11 and 12. The front upright wall 12 of the tray terminates in a handle member 13 pressed into shape so as to enable it to be readily grasped for the purpose of withdrawing the tray from the refrigerator freezing compartment or evaporator unit. The side and end walls 10, 11 and 12 are integral with one another and extend continuously around the four sides of the tray, and the walls 10 and 11 terminate along their upper edges in a rolled rim 14 merging into the handle 13. The metal around the edge of the rim is flanged down a suitable distance to provide a depending apron flange 14a.

The tray frame is formed with a bottom 15 which is drawn in the press operation to provide upstanding intersecting ribs or grid projections 16 and 17. In the present embodiment the rib 16 extends the full length of the tray centrally between the side walls 10 and merges integrally into the end walls 11 and 12. The ribs 17 extend transversely at right angles to the central rib or partition member 16 and form spaced partition members for the reception therebetween of the freezing receptacles. These transverse ribs or partition members 17 preferably have the same height as the longitudinal partition member 16 and merge integrally therewith. In the present embodiment the partition or grid members 16 and 17 extend only partway in the height of the side and end walls of the tray frame, terminating at their upper edges well below the rim 14 of the tray. Intermediate each pair of transverse rib mem-

bers 17 the central rib member 16 is embossed at opposite sides thereof to form inwardly projecting keying projections or lugs 18 which, if desired, may be of wedge shape construction, winding out from their upper ends toward the bottom 15 of the tray frame, with the lower ends of the lugs pressed from the metal in the tray bottom. The side walls 10 of the tray frame are also pressed or embossed at points opposite the lugs 18 to provide generally similar inwardly extending keying projections or lugs 18a.

Thus, it will be seen from the foregoing construction that the tray frame is adapted to be formed by press operations from a single sheet or blank of metal with the central double wall partition member 16 and the transverse double wall partition members 17 dividing the tray frame into individual receptacle receiving spaces and with the bottom 15 of the frame formed integrally with the partition members as well as the side and end walls of the frame. The bottom 15 enables the tray to be slid easily into and out of the freezing unit of the refrigerator while at the same time providing with the walls of the tray and the walls of the partition members large areas of contact for the freezing receptacles, thereby accelerating the freezing of the liquid contents of the receptacles.

For freezing purposes the tray frame of the present embodiment is designed to receive twelve receptacles, cups or molds 19 arranged in two rows at opposite sides of the grid or partition member 16. It will be understood that the tray frame may be constructed to receive a lesser or larger number of cups or molds. In the present instance each mold or receptacle 19 is formed from plastic material of suitable gage or thickness, and in preferred practice the receptacles are molded under heat and pressure from polyethylene plastic material with a wall thickness of approximately thirty thousandths of an inch and preferably not exceeding thirty-five thousandths of an inch. As illustrated, each receptacle or mold 19 is of generally rectangular shape formed with a substantially flat bottom and upright side walls which taper or incline somewhat upwardly and outwardly in order to facilitate removal of the frozen contents. The receptacles are of a size and depth so as to produce cubes or blocks of desired size. The upper marginal edge of each receptacle terminates in a continuous outwardly extending flange 20 which, if desired, may be formed as a rolled edge.

Each receptacle is formed at opposite sides with keyways, grooves or notches 21 extending upwardly from the bottom of the receptacle and of a depth and wedge shape to receive the keying lugs or projections 18 and 18a. Thus, when the receptacles are placed within the tray frame 9 in the spaces formed by the ribs 16 and 17 the lugs or projections 18 and 18a will fit into the pairs of recesses or notches 21 in the receptacles. These lugs or projections 18 and 18a thus serve the purpose of assisting in restraining longitudinal displacement and tilting of the receptacles within the tray frame. The bottom portions 15 of the frame intermediate the grid members 16 and 17 provide contacting heat exchange surfaces over a considerable area of the bottoms of the receptacles 19. Drain holes or apertures 22 of suitable size are preferably punched or pierced in the bottom of the tray frame in the receptacle receiving spaces so as to facilitate drainage of water from the tray

frame after the receptacles have been filled by passing the tray frame and its complement of receptacles under a water faucet.

In the embodiment of the invention illustrated in Figs. 4 to 8 inclusive the tray frame 23 is generally similar to the frame 9, being rectangular in shape and having continuous upright side and end walls 24 and 25 respectively. These walls around three sides thereof terminate at their upper edges in a rolled rim 26 extending continuously around three sides of the tray frame and merging into a handle 27 at the fourth side thereof.

The tray frame 23 is formed with a substantially flat bottom 28 which in the present instance is pressed to provide a central longitudinally extending double wall hollow rib 29 which is of a height materially less than the height of the side and end walls of the tray frame. The bottom 28 of the frame is embossed to provide a series of upwardly extending curved keying projections 30 at each side of the rib 29 and located centrally between the rib and the side walls 24. The bottom of the tray frame 23 is also pierced to provide a suitable number of drain holes 31, and in the present instance a row of such drain holes is provided along each side of the rib 29 and along the base of each side wall 24. As in the case of the drain holes 22 the drain holes 31 in the tray frame 23 serve the purpose of draining excess water out of the tray after the receptacles have been filled.

In the present embodiment the side walls 24 of the tray frame 23 are pressed or embossed to provide inwardly extending keying projections or lugs 32 which may be wedge shaped if desired and which preferably extend substantially the full height of the side walls. The keying projections 32 are in a longitudinal direction staggered with relation to the projections 30, each opposite pair of projections 32 lying on a transverse line extending centrally between a pair of the bottom projections 30.

The tray frame 23 is adapted to receive either twelve individual receptacles or cups generally similar to the receptacles or cups 19 or, as illustrated in Fig. 6, is adapted to receive six double size receptacles 33. Each receptacle 33 is formed of plastic material similarly to the receptacle 19 and is provided with a generally flat bottom 34 terminating in upright longitudinal side walls 35 and end walls 36. These walls incline upwardly and outwardly, as illustrated in Fig. 7, so as to facilitate removal of the frozen contents, and terminate at their upper edges in an outwardly extending flange or rim 37 extending continuously around the four sides of the receptacle. Each receptacle 33 is molded to provide a pair of upwardly extending recesses 38 which are spaced apart in accordance with the longitudinal as well as transverse spacing of the projections 30 in the bottom of the tray frame. Thus, when the receptacle is placed in the tray frame so as to extend longitudinally as shown in Fig. 5, a pair of keying projections 30 in the bottom of the tray frame will fit into the pair of keying recesses 38 in the bottom of the receptacle. Also, when the receptacle 33 is placed in the tray frame so as to extend transversely as shown in Fig. 8, a transverse pair of keying projections 30 at opposite sides of the rib 29 will fit into the pair of recesses 38 in the bottom of the receptacle. It will be seen, therefore, that the cooperating keying projections 30 and recesses 38 will function to locate the receptacles 33 within the tray frame

and restrain displacement thereof both longitudinally and transversely.

Each receptacle 33 in the present instance is also molded to provide a transverse upwardly extending shallow groove or channel 39 extending the full width of the receptacle and terminating at opposite ends in upwardly extending relatively shallow grooves or recesses 40 extending inwardly from the side walls 35 of the receptacle and terminating preferably at the rim 37. Thus, when the receptacles are placed in the tray frame so as to extend longitudinally as shown in Fig. 5, the keying lugs or projection 32 in the side walls of the tray frame will fit into the grooves or recesses 40 in the side walls of the receptacles, hence serving the purpose of assisting in restraining longitudinal displacement of the receptacles. Since the receptacles 33 are of double size it will be observed that the tray frame, constructed as shown in Fig. 4, will receive six of these receptacles, three being adapted to be received at each side of the rib 29 when the receptacles are positioned as shown in Fig. 5. When thus positioned alternate keying projections 32 will extend into the recesses 40 along corresponding outer sides of the receptacles, and the remaining two projections 32 at each side of the tray frame will lie between adjacent end walls of the receptacles in abutting relation thereto, this being permitted by virtue of the fact that the side edges of the projections 32 taper or incline upwardly substantially in accordance with the inclination of the end walls of the receptacles. In the event it is desired to utilize in the tray frame 23 receptacles similar to the receptacle 19, then such receptacles will be positioned between the projections 32 in abutting relation thereto and will be formed with recesses 38 in the bottoms of the receptacles adapted to receive the keying projections 30. In such instance the projections 32 together with the cooperating projections 30 and recesses 38 in the bottoms of the receptacles will, in conjunction with the rib 29, restrain displacement of the receptacles within the tray frame both transversely and longitudinally. In like manner, when the double size receptacles 33 are placed in the tray frame as shown in Fig. 5, the receptacles will be restrained against transverse displacement by the rib 29 and side walls of the tray frame, as shown in Fig. 7.

When the receptacles 33 are placed in the tray frame as shown in Fig. 8 so as to extend transversely thereof, the rib 29 in the bottom of the tray frame will extend into the groove or channel 39 which has a depth to receive fully the rib 29 so as to permit the bottom 34 of the receptacle to lie flat upon the bottom of the tray frame. The rib 29, in conjunction with the transverse groove or channel 39 in the receptacle, will restrain displacement of the receptacle in a transverse direction, while the projections 30 received in the recesses 38 in the bottom of the receptacle will serve to restrain displacement of the receptacle both transversely and longitudinally.

I claim:

1. A liquid freezing tray comprising surrounding side walls and a bottom integral therewith, the bottom being formed with upstanding intersecting ribs providing receptacle receiving spaces therebetween, and said bottom also having drain openings, a receptacle, and projecting means on one of the ribs engaging in a recess in the receptacle for restraining displacement of said receptacle.

2. A liquid freezing tray comprising surrounding side walls and a bottom integral therewith, the bottom being formed with upstanding intersecting ribs providing receptacle receiving spaces therebetween, a plurality of receptacles, and projectings on one of the ribs engaging in grooves in the receptacles for restraining displacement longitudinally of such rib of said receptacles.
3. A liquid freezing tray comprising surrounding side walls and a bottom integral therewith, the bottom being formed with upstanding intersecting ribs providing receptacle receiving spaces therebetween, and said bottom also having drain openings, projections on one of the ribs, and a plurality of freezing receptacles in said spaces resting on said bottom and having recesses receiving said projections.
4. A liquid freezing device comprising a supporting frame having a bottom formed with an upstanding rib, a receptacle removably supported on said bottom and having a bottom and upright side walls, said receptacle bottom having a centrally disposed channel within which said rib extends to provide an interlocking connection between the receptacle and frame.
5. A liquid freezing device comprising a supporting frame having a bottom formed with an upstanding rib, a receptacle removably supported on said bottom and having a bottom and upright side walls, said receptacle bottom having a centrally disposed channel extending from one side wall to the opposite side wall, and said rib projecting into said channel and extending throughout the length thereof.
6. A liquid freezing device comprising a supporting frame having a bottom formed with an upstanding rib, a receptacle removably supported on said bottom and having a bottom and upright side walls, said receptacle bottom having a centrally disposed channel extending from one side wall to the opposite side wall, said rib projecting into said channel and extending throughout the length thereof, said rib and channel providing an interlocking connection between the receptacle and supporting frame.
7. For use with a supporting tray frame constructed and arranged to support a plurality of individual flexible plastic liquid freezing molds and having a bottom provided with an upstanding elongate rib, a flexible plastic individual liquid freezing mold having a bottom provided centrally thereof with a pre-formed channel extending the full width of the bottom and having materially less cross-sectional area than the area of the mold bottom and into which channel said rib is adapted to extend, said mold having surrounding upright walls inclined upwardly and outwardly; the rib of said tray frame when the latter is used with a plurality of said molds forming an interlocking connection with the channels of said molds.
